[57] CLAIM

The ornamental design for a combined labeler and replaceable tape cartridge therefor, substantially as shown and described.

DESCRIPTION

FIG. 1 is a front elevational view of a combined labeler and replaceable tape cartridge therefor showing my new design;

FIG. 2 is a rear elevational view thereof;

FIG. 3 is a bottom plan view thereof;

FIG. 4 is a top plan view thereof;

FIG. 5 is a left side elevational view thereof;

FIG. 6 is a right side elevational view thereof;

FIG. 7 is a front overhead perspective thereof;

FIG. 8 is a front perspective view thereof taken from below;

FIG. 9 is a rear perspective view thereof taken from below;

FIG. 10 is a left side elevational view of the labeler with cartridge removed for clarity of illustration;

FIG. 11 is a front overhead perspective view thereof;

FIG. 12 is a front perspective view of the cartridge portion of my new design;

FIG. 13 is a side elevation view of the tape cartridge showing the new design;

FIG. 14 is a perspective view thereof taken from above; and

FIG. 15 is a perspective view thereof taken from below. The broken line showing of a roll of tape in FIG. 7 is for illustrative purposes only and forms no part of the claimed design.
